UNITED STATES PATENT OFFICE.

WILLIAM SPARKS, OF JACKSON, MICHIGAN, ASSIGNOR TO THE SPARKS-WITHINGTON COMPANY, A CORPORATION OF OHIO.

SIGNAL.

1,274,951.

Specification of Letters Patent.

Patented Aug. 6, 1918.

Original application filed May 11, 1915, Serial No. 27,375. Divided and this application filed October 8, 1915. Serial No. 54,738.

To all whom it may concern:

Be it known that I, WILLIAM SPARKS, a citizen of the United States, and resident of Jackson, in the county of Jackson, in the 5 State of Michigan, have invented new and useful Improvements in Signals, of which the following, taken in connection with the accompanying drawings, is a full, clear, and exact description.

10 This invention relates to certain improvements in signals, and more particularly to a hand operated signal of the mechanically actuated diaphragm type, susceptible of various uses but particularly applicable to 15 automobiles, motor-boats, and other moving vehicles, and is a division of my co-pending application Serial No. 27,375, filed May 11, 1915. Reference is hereby made to my co-pending application Serial No. 800,955, filed 20 November 14, 1913.

The primary object of the invention is to provide a signal which is mechanically operable to give an instantaneous alarm without possibility of failure and susceptible of a multiplicity of speeds, wholly within the control of the operator, for producing sounds of varying character both as to pitch and as to loudness and which may, therefore, be used as a short or long 30 distance signal, and is adaptable to the needs of each case.

Another object is to produce such a signal of simple and comparatively inexpensive construction capable of forcing the vibration 35 of the diaphragm at a sufficient speed so that it will create a note as distinguished from simply a noise or a sound.

Another object is to provide means operable from any predetermined point for forcing the vibration of the diaphragm at any 40 one of the possible speeds desired with only a slight movement of the operator.

Another object is to provide means for returning the operating means to its normal 45 position after each movement, and to provide means allowing such return without forcing diaphragm vibration.

A further object is to provide means either for varying the degree of contact of 50 the diaphragm operating members and therefore the amplitude of the forced vibra-

tion of the diaphragm, or simply as a compensation for ordinary wear.

Other objects and uses appear in the details of construction and arrangement illustrated in the accompanying drawings, in which—

Figure 1 is a side elevation of the device.

Fig. 2 is a vertical central section of the same.

Figs. 3, 4 and 5 are perspective views of the clutch elements.

The invention comprises, as shown, a suitable diaphragm —1— of sheet metal or similar material having a central adjustable 65 contact member —2—. The marginal portion of the diaphragm is secured between the base of a resonator —3— and the flanged end portion —4— of a rear case —5— by means of suitable screws —6—. The rear 70 case —5— carries a stepped bearing —7—, which bearing in turn carries the actuator —8—, rotatably mounted thereon and spaced therefrom by a suitable thrust bearing —9— including rotary balls. This ball bearing 75 may be of any usual and well known construction not herein necessary to further illustrate or describe.

The actuator —8— comprises a flat, substantially circular portion —10— substantially diametrically disposed with respect to the diaphragm and provided with a series of teeth —11— for contact with a suitable wear-piece —2— mounted on and adjustable through the diaphragm —1—, and a 80 lower portion —13— disposed below the toothed portion —10— to form a recess or seat —14—, as shown substantially cylindrical in form and open at the top for the reception of a suitable clutch member —15— 90 positioned therein.

The part —13— is further provided with a depending circular flange —16— adapted to engage the stepped portion of the bearing —7— to normally support and guide 95 the actuator —8— in its rotary movement. Preferably, also, means is provided for holding the actuator to its bearing in all positions of the signal, and for this purpose and as illustrative of one means, a cylindrical 100 sleeve —17— is attached to the wall of the case —5— in any suitable and well known

manner and has its lower end in substantial contact with the upper surface of the flat portion —10— of the actuator, and, for the purpose of economizing in material, the 5 lower portion of the sleeve is formed of sufficient diameter to span the recess —14— while the upper portion of the sleeve is contracted, being of sufficient size, however, at all points to accommodate and allow the 10 free passage of a shaft —18— having a spirally arranged portion —19— positioned within the case —5— and extending through registering openings in the clutch member —15— and the actuator —8—.

15 The ball bearing —9—, and stepped bearing —7—, are also provided with openings forming a conduit —20— registering with the openings through the actuator and the clutch member, and this conduit, in this 20 specific illustration, is closed by a suitable tubular boss —21— having a threaded relation with the case —5— and stepped bearing —7—, as shown. The conduit contains a suitable spring —22— for normally holding 25 the shaft —18— at substantially its limit of upward movement, and the shaft may, as shown, be provided with a suitable flat head —23— forming a bearing for the spring.

30 The clutch member, in this specific illustration, is identical with that disclosed in my co-pending applications heretofore referred to, and comprises a suitable nut —24— provided with a central spirally formed opening —25— adapted to fit the spiral portion —19— of the shaft, so that longitudinal movement of the shaft through the nut will cause rotation of the nut, the shaft being held from rotary movement by the engagement 35 of the square upper portion thereof with a square opening —26— through the case —5—.

The nut is arranged within a casing comprising the recessed section —27— and closure section —28— arranged, in this specific 45 illustration, with the recessed section —27— uppermost and inverted, and the closure section may be secured thereto in any suitable manner, and, in this specific instance, openings are illustrated for the reception of 50 screws for uniting the parts. The section —28— is provided with lugs —29— extending inwardly in assembled condition of the clutch member and adapted for contact with 55 teeth —30— upon the adjacent face of the nut —24—.

The recess in section —27— is sufficiently deep to allow the nut —24— to be raised by 60 upward movement of shaft —18— to a position at which the teeth thereon will not engage the lugs —29—. In other words, the recess within the case is of sufficient depth or size to allow nut —24— with the teeth thereon to move out of engagement 65 with the lugs upon the case so that the nut

may freely rotate within and with respect to the case. When the nut is moved downwardly by a downward movement of shaft —18—, the teeth upon the nut come into engagement with the lugs —29— upon the 70 case to prevent rotation of the nut while the shaft —18— is moved in that direction.

The section —27—, in this specific illustration of the casing, is rigidly secured to the actuator —8— and within the recess —14— thereof by a suitable set screw —31—, whereby rotation of the clutch member causes rotation of the actuator —8—.

When the shaft —18— has reached the limit of its downward movement and is released, the spring —22— will automatically return it to starting position. Preferably, the shaft —18— is provided with a suitable knob or handle —32— of any suitable or desired construction or form.

It will be apparent now that by pressing downwardly upon the handle —32—, the nut —24—, the case comprising the members —27— and —28—, and the actuator —8— will be rotated in unison, the teeth —11— of the actuator by contact with the wear-piece —12— causing a forced vibration of the diaphragm. When the handle —32— is released, the spring —22— automatically raises the shaft, which in turn 95 raises the nut —24— so as to release the teeth —30— from engagement with the lugs —29—. The nut —24— will then freely rotate within its case and allow the shaft to be automatically returned upwardly by the 100 spring without rotation of the shaft or of the actuator —8—.

Although I have shown and described one particular construction, method of assemblage, and manner of operation of the device, I do not desire to limit myself to the same, as many changes may be made in the details of assemblage, relative engagement and form of the parts, without departing from the spirit of this invention as set forth 110 in the claims.

What I claim is:

1. In a signal, a diaphragm, a diaphragm actuator, a spiral shaft, a nut mounted on said shaft, a case inclosing the nut, and 115 mechanism for causing the actuator to rotate with said case.

2. In a signal, a diaphragm, a spiral shaft, a diaphragm actuator substantially coaxial with said shaft and having a central recess, a clutch case positioned in the recess, a nut correlated with the spiral shaft and clutch case so that rotation of the nut in one direction causes rotation of said clutch case, and means for causing the actuator to rotate 120 in unison with said case.

3. In a horn, a diaphragm having a wear-piece thereon, a casing at the rear of the diaphragm, a tubular bearing mounted within the casing, an actuator rotatably 125

5 mounted upon the tubular bearing, a spiral shaft adapted to be projected through the actuator and into the tubular bearing, a nut mounted on said shaft, a casing inclosing the nut, rigid connections between the said casing and the actuator, and means on the said casing for engaging the nut to prevent rotation of the nut within said casing when the shaft is moved in one direction and

permitting free rotation of the nut within 10 the casing when the shaft is moved in the opposite direction.

In witness whereof I have hereunto set my hand this 27th day of September, 1915.

WILLIAM SPARKS.
